AUTOMATICALLY OPERATED WIND RESPONSIVE WINDOW VENTILATOR
 Leon Albert Van De Veire, 26347 Edison Road,
 South Bend, Ind.
 Filed Apr. 7, 1958, Ser. No. 726,906
 12 Claims. (Cl. 98—95)

This invention relates to improvements in ventilators, and more particularly to a ventilator of the jalousie type.

The primary object of this invention is to provide a ventilator of this character which is of simple construction, which is easily installed in and removed from a window, which may be set in any selected position and will retain this position.

A further object is to provide a device of this character having means responsive to wind pressure for closing the same and having means for restoring the construction to open position after wind pressure subsides.

Other objects will be apparent from the following specification.

In the drawings:

FIG. 1 is a face view of the device installed in a window;

FIG. 2 is an enlarged vertical sectional view taken on line 2—2 of FIG. 1;

FIG. 3 is a fragmentary enlarged transverse sectional view taken on line 3—3 of FIG. 2;

FIG. 4 is a vertical sectional view taken on line 4—4 of FIG. 5;

FIG. 5 is a rear vertical sectional view taken on line 5—5 of FIG. 6;

FIG. 6 is a vertical sectional view taken on line 6—6 of FIG. 5;

FIG. 7 is an enlarged fragmentary detail sectional view taken on line 4—4 of FIG. 5;

FIG. 8 is a view of a spring as viewed from the top in FIG. 7;

FIG. 9 is an enlarged fragmentary detail sectional view of another portion of the device taken on line 4—4 of FIG. 5;

FIG. 10 is an enlarged fragmentary detail sectional view taken on line 5—5 of FIG. 6, and illustrating the same parts shown in FIG. 9;

FIG. 11 is an enlarged fragmentary detail sectional view taken on line 4—4 of FIG. 5, and illustrating another detail of the construction, with the parts thereof shown in one position;

FIG. 12 is a detail sectional view taken on line 4—4 of FIG. 5 and illustrating the same parts shown in FIG. 11 in a different operative position;

FIG. 13 is an enlarged fragmentary detail sectional view taken on line 13—13 of FIG. 6;

FIG. 14 is a schematic view illustrating the parts of the device in closed position;

FIG. 15 is a schematic view illustrating the parts of the device in fully open position;

FIG. 16 is a schematic view illustrating the parts in open position, with one part thereof shifted to condition the device for automatic operation;

FIG. 17 is a schematic view illustrating the position of the parts in fully automatic position, with the louvers open;

FIG. 18 is a schematic view illustrating the relation of the parts in schematic view operated toward closed position in response to wind pressure upon the device;

FIG. 19 is a perspective view of a locking element used in conjunction with the device; and

FIG. 20 is an enlarged fragmentary detail sectional view taken on line 6—6 of FIG. 5, and illustrating a modification of the device.

Referring to the drawings which illustrate the preferred

2

embodiments of the invention, the numeral 25 designates the frame for a double-hung window having an upper sash member 26 and a lower sash member 27 slide vertically in lateral guides provided by stops 28 of the frame which also includes the sill portion 29. A window screen unit 30 may be mounted in the window frame bearing upon the sill 29 and located outwardly of the outer stop 28 shown at the right in FIG. 3.

As best seen in FIG. 3, a pair of opposed upright members are carried by the window frame. Each upright member is preferably a channel including a base portion 32, side portions 33, and inwardly offset leg portions 34. The channels are mounted at each side of the frame with the leg portions 34 thereof positioned between the stops 28 which guide the lower sash 27. The channels and associated parts to be described are held in place by a locking unit of the character illustrated in FIG. 19 and including a longitudinal web 35 bearing flat against one side 33 of the channel and a flange 36 interposed between the innermost stop 28 and an offset in one leg of the channel 34. At its upper end the stop has a transversely extending U-shaped part 37 adapted to receive the lower portion of the lower sash 27 when elevated. The lower portion of the locking member 35 has an offset flange 38 adapted to bear against the inner trim member 39 at the bottom inner side of the window sash. A stick or strut 40, FIG. 1, positioned between the upper edge of the elevated lower sash 27 and the top of the window frame 25 holds the sash 27 in firm engagement with the parts 37 of the locking units 35. Each of the channel bases 32 has pivoted therein a plurality of pivot pins 42 in longitudinal alignment and equally spaced relation. The pivot pins are so arranged that the pins of opposite channels will be axially aligned. Each pin mounts a vertically elongated channel or socket 43 closed at its bottom at 44 and serving to receive one end of a glass pane or louver member 45 which spans the space between adjacent channels 32. The channels and panes are confined in operative position by flanges 35 of the locking unit.

The socket members 43 are pivoted at or slightly above the center thereof, and the lowest socket is pivoted from the bottom of each channel a distance equal to the spacing between the lower edge of the socket and the pivot so that the bottom edge of the socket will bear against the sill 29 when in the closed position illustrated in FIG. 2. The spacing between the pivots 42 is less than the vertical dimension of each glass pane 45 so that the panes lap each other in the closed position illustrated in FIG. 2 and lie in parallel planes. If desired, abutment members 46 may be mounted on the channels to be interposed between the adjacent sockets 43 in the closed position of the panes, as illustrated in FIG. 2, and such stop means or spacers may include abutment members 47 projecting inwardly adjacent to the top edge of the adjacent innermost louver to form a stop means preventing withdrawal of the panels 45 from the sockets when the ventilator is in closed position but not interfering with sliding of the panels from the sockets when the panels are in an open position, for example, in the position illustrated in FIG. 6.

In the preferred construction, the channels at their upper ends fixedly mount carriers 48 extending to a level preferably slightly above the level of the uppermost pin 42. The carrier 48 forms means for mounting the ends of a pane 49 above and outwardly of the uppermost full pane 45 for purposes to be described.

Each of the pivot pins 42 fixedly mounts thereon the hub portion 50 of an arm or link 51. The arms or links 51 as illustrated in FIG. 4, are of equal length and each of the arms, except arm 51a connected to the uppermost pivot pin 42, is pivotally connected at 52 to an elongated

lower bar or rod 53 at points on said rod spaced apart the same distance as the spacing between adjacent pivot pins 42. By this arrangement each of the louvers, panels or panes 45, except the uppermost pane in some instances, is connected to and caused to swing equally and simultaneously with the others. The bar 53 of one channel preferably has an offset 54 adjacent its upper end to which is pivoted at 55 a link 56 which in turn is pivoted at 57 to another link or bar 58, extending substantially parallel to and alongside bar 53, all as illustrated in FIG. 4.

A manual latch mechanism or locking device, by means of which the angular position of the panes 45 may be controlled, is provided in the device. As best illustrated in FIGS. 3, 4, 5, 6 and 13, the base 32 of one channel has an elongated longitudinal slot 59 formed therein intermediate its height to accommodate slidably therein a bracket member 60 carried by bar 58, as best seen in FIG. 13. Bracket 60 preferably includes an upwardly extending portion 61 and a substantially horizontally projecting portion or member 62. A bellcrank member is pivoted at 63 to the bracket. One leg 64 of the bellcrank carries a pin or pins 65 at its free end adapted to seat in a selected one of a series of spaced holes or apertures 66 located alongside the slot 59 in the channel base 32. The other leg 67 of the bellcrank is pivoted at 68 to a trigger or actuating member 69 which preferably has a slidable connection with a pin 70 carried by the member 62, which pin is encircled by a coil spring 71 serving normally to press the actuator 69 in a direction to cause the pin 65 of the bellcrank to seat in an aperture 66 in the channel base. Movement of the actuator 69 from the full line to the dotted line position shown in FIG. 13 withdraws the bellcrank and the pin 65 to permit sliding of the bracket 60 relative to the channel base 32. If desired, means may be provided to hold the actuator 69 in releasing position, which means may take the form of a hook or other retainer 72 carried by the member 62 and engageable in an aperture 73 in the actuator 69, as illustrated in dotted lines in FIG. 13.

The uppermost pivot pin 42 and its associated pivot arm 51a preferably has pivotally connected thereto at 75 the upper end portion of an elongated bar 76 which has a lost motion connection with lower bar 53, as by means of an elongated longitudinal slot 77 formed therein at its lower end and receiving a pin 78 fixedly carried by the upper end of the bar 53. Spring means are provided to releasably hold the slotted bar 76 in the position illustrated in FIG. 11, with the pin 78 of the bar 53 at the upper end of the slot 77 thereof and with the bars 76 and 53 substantially parallel to one another. Such spring means are here shown as an elongated leaf spring 79 anchored to the slotted bar 76 at 80 above the slot 77 and positioned against free swinging movement as by means of a second anchor pin 81 adjacent to the pin 80 and adapted to be straddled by parts of the spring 79 at opposite ends of a loop thereof extending around the pin 80. The spring 79 has a laterally projecting portion 82 intermediate its ends and so spaced relative to the slot 77 as to lock the pin 78 at the upper end of said slot, as seen in FIG. 11. The spring terminates in a free laterally offset end portion 83 which preferably extends to a level adjacent and preferably below the lower end of the slot 77.

An elongated latch lever or rod 85 extends lengthwise in each channel 32, 34 and preferably has an offset 86 (FIG. 4) formed therein adjacent its lower end at which the same is pivoted by a pivot pin 87 at a point substantially aligned with the pivot pins 42. The offset 86 in the rod or lever permits the rod to extend vertically and substantially parallel to the line between the pivot pins 42 but alongside the same, as best seen in FIG. 4. The lower end portion of the pivoted rod or lever 85 cooperates with rod-latching means. Thus rod 85 has pivotally connected thereto at 88 a latching bellcrank or latch abutment member having a depending arm 89 and an

upper arm 91 projecting laterally from rod 85 and terminating in a foot portion or shoe 92. The free end of the depending arm 89 is engageable with a stop member or pin 90 carried by the rod 85 to limit pivoting of the bellcrank on the rod 85 in clockwise direction as seen in FIGS. 4 and 9. The foot portion or shoe 92 of the arm 91 is adapted to bear against an abutment on bar 53, such as a protruding or abutment portion of the pivot pin 52' interconnecting the lowermost pivot arm 51 with the lower end of the bar 53, as illustrated in FIGS. 9 and 10. Thus latch rod or lever 85 and latching abutment or bellcrank 89, 91 with the pins 90 and 52' comprise a second latch which cooperates with the louver interconnecting bar 53 to latch the louver interconnecting means and the louvers connected thereby in open position independently of the manual latch mechanism. The latching bellcrank part 91 has a plurality of apertures 93, in a selected one of which is anchored one hook end portion of an elongated coil spring 94 whose opposite end has a hook portion engageable with a selected one of a plurality of longitudinally spaced pins 95 carried by the lower free end portion of the latch rod 85. The arrangement of the spring is such that the pressure which it exerts upon the bellcrank 89, 91 is determined by the selection of the pin 95 at which its lower end is anchored and of the aperture 93 at which its upper end is anchored.

The pivotal position of the latch rod or lever 85 is normally steadied by a leaf spring or elongated wire spring 98 having one end 99 thereof anchored to a side wall of the channel at 100, as seen in FIG. 4. The spring has an offset portion 101 thereof intermediate its ends, and the free end portion 102 thereof is preferably bent, as best seen in FIG. 8. The bend 102 serves to normally hold the latch rod 85 in vertical position, as illustrated in full lines in FIG. 7, and when the latch rod is swung to the dotted line position shown in FIGS. 7, 8 and 9, the offset or shoulder 101 of the spring serves to hold it in that pivoted position.

A latch-rod-tripping bracket of generally F-shape is pivoted upon the pivot pin 42 mounting the link 51 pivoted to the upper end of the bar 53. This bracket has a lower portion 105 engageable with a side wall 33 of the channel in the position illustrated in FIG. 11 and spaced therefrom in the position illustrated in FIG. 12. An upwardly projecting portion 106 of the bracket is bent at its end and terminates in a stop 107 engageable with the latch rod or lever 85 at the side of the rod opposite that adjacent the pivot pin 42 so that the latch rod 85 is positioned between the pivot pin 42 and the stop 107. A central lateral leg 108 of the bracket terminates in a foot portion 109 having a cam edge engageable by a pin 110 carried by the lower free end of the slotted bar 76. The arrangement is such that, if the upper panel 45' is tilted downwardly from an arrangement in which all panels 45 are fully open, as illustrated in FIG. 15, to the position in FIG. 16, the slotted bar 76 is moved bodily upwardly and the pin 110 bears against the end face of the bracket shoe 109 to tilt the bracket from the position shown in FIG. 11 to that shown in FIG. 12. The result of the tilting action is that the stop 107 engages the latch rod 85 and swings or trips the rod from the position shown in FIG. 11 to that shown in FIG. 12.

A latch-rod-positioning bellcrank is pivoted on the uppermost pivot pin 42. The bellcrank has a depending arm or leg 115, see FIG. 7, terminating in a shoe abutment 116 bearing against the latch rod or lever 85. A lateral arm 117 of the bellcrank has a shoe abutment 118 bearing against the upper edge of the adjacent leg 51a. A spring normally assists in urging the bellcrank to the dotted line position shown in FIG. 7 for the purpose of urging the latch rod 85 to the dotted line position in said figure. As here shown the spring has a portion 119 loosely coiled around the pin 42 and an end portion 120 bearing against the adjacent side wall 33 of the channel. The opposite end 121 of the spring terminates in a hook

which engages in one of a group of apertures 122 formed in the bellcrank arm 117 to adjust the tension applied by the spring to the latch rod 85.

One of the pivot pins 42, see FIG. 4, here shown as an intermediate pin, pivotally mounts a bellcrank having an upwardly projecting arm 125 engageable with a side wall 33 of the channel. A lateral arm 126 of the bellcrank has a projection 127 engageable with the bottom edge of the adjacent link 51. A spring 128—129 resists movement of the bellcrank 125, 126 in a clockwise direction from the position shown in FIG. 4 and thereby opposes downward movement of bar 53 in a selected range of its movement. This spring may constitute a wire portion coiled around the pivot pin 42 and having an end portion 128 bearing against the channel wall 33. The opposite end 129 of the spring is anchored to the portion 126 of the bellcrank. Spring 128, 129 facilitates automatic closing of the louvers as hereafter described.

Spring means serve to adjustably press the rod 53 in a downward direction and acts in opposition to spring 128, 129. As here seen, said spring means may constitute a wire spring loosely coiled around one of the pivot pins 42 having one end 130 thereof bearing against channel wall 33 above the pin 42 and the opposite end 131 thereof hooked in an aperture of the adjacent link 51b. In order to provide adjustment of the downward spring pressure, the adjacent link 51b may be provided with a series of openings or apertures 132 selectively engageable by the spring end 131.

In the position of the parts shown in FIG. 4, the louvers or panes 45 are all partially open, and the setting thereof is determined by the manual latch mechanism illustrated in FIG. 13, and particularly by the vertical position of that latch mechanism in the slot 59 and the point at which one or more of the pins 65 thereof engage a hole or holes in a set of holes 66. The manual latching mechanism serves to hold the louvers in the selected position, and a wide range of positions may be provided determined by the number of holes or apertures 66 and the spacing thereof. The upper portions of both FIGS. 4 and 6 illustrate various angular positions which the louvers or panels 45, 45' may assume, and it will be understood that these positions are illustrative only, and it will further be understood that all of the louvers or panels 45 and 45' may assume each of these angular positions in unison. The range of angularity will preferably extend from a fully closed position, as illustrated in FIG. 14, to a fully open position as illustrated in FIG. 15.

If it is desired to condition the ventilator or jalousie in open position, to be closed, however, in the event wind pressure develops, the following sequence of operations is performed. The panels 45 are first moved to fully open position with the bar 53 in its lowermost position as illustrated in FIG. 15. Then while the remaining panels 45 are held fully open, the uppermost panel 45' is tilted to the FIG. 16 position. This tilting action of the upper panel 45' is accommodated by release of part 82 of spring 79 from pin 78 on bar 53 and by upward endwise movement of the slotted bar 76 relative to the lower slotted bar 53. As the bar 76 moves upwardly, the pin 110 thereon strikes the cam edge of the shoe 109 of the adjacent latch-tripping bracket bellcrank, and tilts that bracket counterclockwise, as viewed in FIG. 12, so that the bracket stop or abutment 107 engages the latch rod or lever 85 and swings the same toward the position shown in FIG. 12. This swinging movement of the latch rod 85 carries with it the rod-latching bellcrank lever 89, 91 at its lower end, see FIG. 9, which is normally urged by the spring 94 to a position with its depending leg 89 bearing against the stop 90 on the latch rod 85. The latching bellcrank lever 89, 91 is spaced from the rod pivot 87 so that the latching bellcrank 89, 91 moves bodily toward the bar 53 and into a position in which the

shoe 92 thereof bears upon or intercepts the stud 52' when the bar 53 has been lowered to its full extent to accommodate full opening position of the louvers, as explained above and as illustrated in FIG. 15. Consequently, when the shoe 92 of the latching bellcrank 89, 91 locks on the lug 52' and is held by the action of the spring 94, the bar 53 is held in lowered position, as shown in full lines in FIG. 9, and as shown in FIG. 17. This locking action by the latching bellcrank 89, 91 holds the louvers 45 in nearly open position without the locking device shown in FIG. 13. Consequently, the locking device shown in FIG. 13 may be rendered inoperative by moving the actuator 69 thereof to the dotted line position shown in FIG. 13 and holding it in that position by the use of the retainer 72. It may be mentioned that the movement of the bar 53 to its lower position shown in FIG. 9 from a position as shown in FIG. 4 is free of contact by the pin 52' with the foot 92 of the latching bellcrank 89, 91 when the latch rod 85 is in the dotted line position shown in FIGS. 7 and 9. The dotted line position of the latch rod 85 in FIGS. 7 and 9 is attained whenever the louvers assume closed position, either by manual or automatic operation, by the action of the latch-rod-positioning bellcrank 115, 117, best seen in FIG. 7. Also, it may be noted that the spring 79, 83 associated with the elongated slot 77 of slotted bar 76, as seen in FIGS. 11 and 12, allows the louvers 45 and 45' to resume operation in unison and parallel positions upon closing of the louvers again by either manual or automatic operation. As in the arrangement of the rod-latching bellcrank 91, 92 above explained, so also the latch-rod-tripping bracket 106, 109 of FIGS. 11 and 12 is clear of contact with any pins associated with the bars 53 or 76, due to the circular arc of travel of the links 51, until such time as the latch rod 85 is moved to the full line position in FIG. 12 so that the pin 110 engages foot 109 of the bracket as said pin moves upward with slotted bar 76 when louver 45' is tilted from its position in FIG. 15 to its position in FIG. 16. After the pin 110 passes the foot 109, the lever 106, 108 is free to return to the FIG. 11 position and thereby condition it for the next action.

As the upper louver 45' is tilted from the FIG. 15 position to the FIG. 16 position, the latch-rod-positioning bellcrank 115, 117 is pivoted by the movement of the arm or link 51a from the full line to the dotted line position shown in FIG. 7. As this pivotal movement occurs, the shoe 116 of the leg 115 of the latch-rod-positioning bellcrank serves to push the latch rod or lever 85 from the full line to the dotted line position in FIG. 7 whenever the wind acting upon the louver 45' tilts the same, as illustrated in FIG. 18.

The bellcrank 125, 126 cooperating with its associated link 51 under the influence of the spring 128, 129 serves as means to assist closing of the louvers in response to wind pressure. This bellcrank is so associated with link 51 and the channel wall that it is free to move only between a partly open position and a fully open position. In other words, the leg 125 bears against the side wall 33 of the channel when the unit reaches a partly open position. Movement of the close-assisting bellcrank 125, 126 from partly open to fully open louver position occurs against the reactance or resistance of the spring 128, 129 so that the spring is under substantial tension in the FIG. 16 open louver position of the parts. The spring tension is substantially relaxed when the louvers reach the partly open position shown in FIGS. 4 and 18. The principal function of the bellcrank lever 125, 126 is to assure closing movement of the louvers by wind pressure and to limit the extent to which the louvers 45 will reopen after abatement of wind pressure substantially at the position shown in FIGS. 4 and 18. In one construction the limitation upon reopening of the louvers imposed by the close-assisting bellcrank lever 125 is an open position of approximately 30 degrees. However, it will be apparent that the shape and arrangement of the lever will determine this

factor and that it may vary substantially according to the wishes of the fabricator.

The spring 130 serves as means tending to open the louvers for ventilation after the mechanism has been tripped and at such time as the wind pressure which caused the tripping action has abated or reduced. The spring has several adjustments accommodated by the adjustment openings 132 in arm 51b and the setting or adjustment of the spring controls or adjusts the reopening force exerted by the spring 130. It will be understood that in some instances, depending upon the balance or unbalance of the louvers relative to pivot pins 42, it is not necessary to use a spring 130. Also it will be understood that the close-assisting bellcrank lever 125, while preferred, is optional and is not required.

To recapitulate the operation of the device in response to wind pressure, the manual latch mechanism 62—72 is first actuated to inoperative position, as seen in dotted lines in FIG. 13, and is held in that position by the locking of retainer 72 in aperture 73 of actuating member 69. The louvers 45 are then moved to the FIG. 15 position and are held in that position manually while the uppermost louver 45' is tilted from the FIG. 15 to the FIG. 16 position to extend the slotted upper connecting bar 76 from the position illustrated in FIG. 11 to that illustrated in FIG. 12. Thereupon, the louvers are released and assume an open position substantially as illustrated in FIG. 17, being positioned by springs 94 and 130 acting thereon and tending to hold the bar 53 adjacent its lower limit, that is, near the position shown in FIG. 9. Thereupon, whenever wind pressure is exerted against the structure, the effective force thereof will be substantially that effective upon the lower portion of the louver 45' below the stationary upper louver or pane 49, as illustrated by the arrow in FIG. 18. When strong gusts of wind arise the louvers tend to close; and when the wind pressure reduces the louvers tend to reopen. The spring 120, 121 is so selected that a predetermined wind pressure must exist before the louver 45' and latch lever 85 can swing against said spring 120, 121 to release the rod latch bellcrank 89, 91 from pin 52' on louver bar 53 and thus free the louvers to be swung toward closed position by spring 128, 129. As a result of this arrangement a householder may be assured against blowing of rain into a building when the ventilator is unattended with the louvers thereof in the open position shown in FIG. 17. Thus the louvers may be set for automatic operation in response to wind pressure whenever that is desired and, if wind pressure develops which commonly accompanies stormy conditions, or which tends to permit entry of rain through the open louvers, the louvers close automatically in response to the wind pressure and stay closed as long as the wind pressure continues. Since leakage is slight except at times when wind pressure exists, this arrangement makes effective a full sealing condition of the window at all times, and at the same time provides ventilation until such time as protection against windblown rain is required.

Further protection of a different nature is provided by means of the unit shown in FIG. 19. The primary purpose of this unit is to make the device burglar-resistant by blocking the upper open ends of the sockets 43 to prevent removal of the louvers or panes 45 in all but the closed position. Members 47 prevent removal of the louvers from their sockets 43 when in closed position. A secondary purpose of part 35 of the locking unit is to provide an attractive appearance of the device.

In the embodiment shown in FIG. 20, a yielding resilient channel-shaped binder strip 145, preferably formed of rubber or synthetic resin, is mounted upon the upper margin of each louver or pane 45. Strip 145 has a laterally projecting flange 146 engageable with the adjacent pane when the panes are in closed position as shown in FIG. 20. The strip 145 thus seals the gaps between panes or louvers in cold weather and also repels wind-driven

rain from flowing upwardly thereon and over the top edge thereof if the device is positioned in one of the locked positions provided by the latch 60—73.

While the preferred embodiment of the invention has been illustrated and described, it will be understood that changes in the construction may be made within the scope of the appended claims without departing from the spirit of the invention.

I claim:

10 1. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means and operative to lock said link means, interconnecting means and group of louvers in selected position, said manual latch having a louver releasing position, a second latch, and means responsive to movement of the independent louver for tripping said second latch, said second latch cooperating with said interconnecting means to releasably hold said interconnecting means and said group of louvers in open position independently of said manual latch, said second latch including a vertical latching lever pivoted intermediate its ends and a latch abutment member carried by and projecting laterally from said lever spaced from the pivot to be bodily shiftable toward and from said interconnecting means, and an abutment on said interconnecting means engageable by said lever-mounted latch abutment member.

20 2. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means for locking said link means, interconnecting means and group of louvers in selected position and having a louver-release position, a second latch engaging said interconnecting means to normally releasably hold said interconnecting means and said group of louvers in open position independently of said manual latch, said second latch including a vertical lever pivoted intermediate its ends, and a latch abutment member carried by and projecting laterally from said vertical lever spaced from its pivot to be bodily shiftable toward and from said interconnecting means, an abutment on said interconnecting means engageable by the latch abutment member of said second latch, lock motion means connecting said interconnecting means and the louver independent of said interconnecting means, and means responsive to movement of said independent louver for pivoting said vertical lever to release the latch abutment member of said second latch from the abutment on said interconnecting means.

30 3. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means for locking said link means, interconnecting means and group of louvers in selected position and having a louver-release position, a second latch engaging said interconnecting means to normally releasably hold said interconnecting means and said group of louvers in open position independently of said manual latch, said second latch including a vertical lever pivoted intermediate its ends, a second lever pivoted to said vertical lever spaced from its pivot to be bodily shiftable toward and from said interconnecting means, said second lever pivot-

ing in a limited range relative to a stop member on said vertical lever, an abutment on said interconnecting means engageable by said second lever, lost motion means connecting said interconnecting means and the louver independent of said interconnecting means, means responsive to movement of said independent louver for pivoting said vertical lever to release said second latch lever from the abutment on said interconnecting means, and resilient means normally urging said second lever into engagement with the stop member on said vertical lever.

4. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch having a variety of operative positions and a released position and connected to said link means for locking said link means, interconnecting means and group of louvers in selected position, a spring-urged second latch, said second latch including an abutment member shiftable on an upright member for engaging said interconnecting means at an abutment thereof to releasably hold said interconnecting means and said group of louvers in open position independently of said manual latch, lost motion means connecting said interconnecting means and the independent louver, means responsive to closing movement of said independent louver for shifting said spring-urged second latch to disengage said abutment member from the abutment of said interconnecting means, said lost motion means including a bar pivoted relative to said independent louver and means providing a pin and slot connection between said bar and said interconnecting means, and means for releasably positioning said bar in predetermined relation to said interconnecting means when said manual latch is in released position.

5. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means for locking said link means, interconnecting means and group of louvers in selected position and having a louver-release position, a spring-urged second latch, said second latch including an abutment member shiftable on an upright member for engaging said interconnecting means at an abutment thereof to releasably hold said interconnecting means and said group of louvers in open position independently of said manual latch, lost motion means connecting said interconnecting means and the louver independent of said group, means responsive to closing movement of said independent louver for shifting said spring-urged second latch to disengage said abutment member from the abutment of said interconnecting means, said lost motion means including a bar pivoted relative to said independent louver, and means providing a pin and slot connection between said bar and said interconnecting means, a resilient latch carried by said bar and a second abutment carried by said interconnecting means and releasably engaged by said resilient latch.

6. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means for locking said link means, interconnecting means and group of louvers in selected position and having a louver-release position, a spring-urged second latch, said second latch including an abutment member

shiftable on an upright member for engaging said interconnecting means at an abutment thereof to releasably hold said interconnecting means and said group of louvers in open position independently of said manual latch, lost motion means connecting said interconnecting means and the louver independent of said group, means responsive to closing movement of said independent louver for shifting said spring-urged latch to disengage said abutment member from the abutment of said interconnecting means, said lost motion means including a bar pivoted relative to said independent louver and means providing a pin and slot connection between said bar and said interconnecting means, an elongated resilient member fixedly secured at one end to said bar and including a hook portion intermediate its ends, and a second abutment on said interconnecting member releasably engaged by said hook portion, said resilient member having an elongated free end portion engageable with said second abutment through the full range of movement of said lost motion means.

7. A ventilator comprising a pair of upright members adapted to be mounted in a window frame, a plurality of horizontal louvers pivoted at their ends to said uprights and adapted to partially overlap when closed, means interconnecting a group of selected louvers for substantially simultaneous and equal pivotal movement, means automatically cooperating with said interconnecting means for releasably locking said group of louvers in open position, lost motion means connecting another of said louvers with said interconnecting means, resilient means normally positioning said other louver in predetermined angular relation to the louvers of said group when the latter are held open by said locking means, means responsive to pivotal movement of said other louver toward closed position while the louvers of said group are held open by said locking means for releasing said locking means, and resilient means urging said group of louvers toward partially open position.

8. A ventilator comprising a pair of opposed upright members, a plurality of louvers pivoted to said upright members and adapted to overlap in closed position, means interconnecting a group of said louvers for simultaneous and equal pivotal movement, one louver being independent of said group, a latch assembly having an abutment member engaging said interconnecting means to releasably hold said interconnected louvers in open position, and means responsive to wind conditions acting on said independent louver for disengaging said latch abutment member from said interconnecting means whereby the exposure of the overlapping portions of the louvers to the wind tends to close said louvers.

9. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means and having a releasing position and a plurality of louver-locking positions, a second latch having an abutment member engaging said interconnecting means to releasably hold said interconnected group of louvers in open position when said manual latch is in releasing position, lost motion means connecting said interconnecting means and the louver independent of said group of louvers and having a first adjustment, whereby said last named independent louver may be set at an angle different from said open position of said group of louvers as set by said second latch to respond to wind pressure and means for releasably latching said lost motion means in a second adjustment for similarly positioning all louvers.

10. A ventilator comprising a pair of opposed upright members, a plurality of louvers pivoted to said upright members and adapted to overlap in closed position, means

interconnecting a group of said louvers for simultaneous and equal pivotal movement, one louver being independent of said interconnecting means, link means carried by said interconnecting means, a manual-latch connected to said link means for locking said interconnected louvers in selected position, said latch having a louver-releasing position, a spring-urged second latch assembly including an abutment member engaging said interconnecting means to releasably hold said interconnected louvers in open position independently of said manual latch, lost motion means connecting said interconnecting means and the louver independently of said group and having an adjustment whereby said independent louver may be set at an angle to respond to wind pressure and different from the open setting of said group of louvers by said second latch, and means responsive to closing movement of said independent louver from said last mentioned setting for shifting said spring-urged second latch to disengage said latch abutment member from said interconnecting means.

11. A ventilator comprising a pair of opposed upright members, a plurality of louvers pivoted to said upright members and adapted to overlap in closed position, means interconnecting a group of said louvers for simultaneous and equal pivotal movement, one louver being independent of said interconnecting means, link means carried by said interconnecting means, a manual latch connected to said link means and having a releasing position and a plurality of louver-locking positions, a second latch including an abutment member engaging said interconnecting means to releasably hold said interconnected louvers in open position when said manual latch is in releasing position, wind responsive means for tripping said second latch to disengage said latch abutment member from said interconnecting means, whereby the louvers are

free to close in response to wind pressure, and spring means normally urging said louvers toward partially open position.

12. A ventilator comprising a pair of opposed upright members adapted to be mounted in a window frame, a plurality of pairs of spaced registering sockets, one socket of each pair being pivoted to each upright member, a plurality of panels each supported at opposite ends by a pair of said registering sockets and adapted for overlapping relation in closed position, a lever carried by each socket, a bar pivoted to and interconnecting a group of adjacent levers, a manual latch means connected to said bar and having a release position and a plurality of panel-locking positions, a second bar pivoted to a lever which is independent of said group of levers, said second bar having a lost motion connection with said first bar, releasable means for normally positioning said bars in predetermined relation, means pivoted to an upright member and mounting an abutment member for engaging and cooperating with said first bar for releasably locating the first bar and thus the sockets associated therewith in open position, resilient means normally urging said sockets toward partially open position, and means responsive to movement of said second bar by reason of wind pressure on the panel carried by said independent socket for tripping said releasable means to disengage said abutment member from said first bar.
